UNITED STATES PATENT OFFICE.

ALFRED HERZ, OF CHICAGO, ILLINOIS.

PNEUMATIC-TUBE SYSTEM.

1,069,062.

Specification of Letters Patent.

Patented July 29, 1913.

Application filed May 20, 1912. Serial No. 698,553.

To all whom it may concern:

Be it known that I, ALFRED HERZ, a citizen of the United States, and a resident of the city of Chicago, county of Cook, and State 5 of Illinois, have invented certain new and useful Improvements in Pneumatic-Tube Systems, of which the following is a specification.

My invention relates to improvements in 10 pneumatic tube systems and has for its object the provision of a system of this character having improved means for introducing cartridges thereto.

A further object of the invention consists 15 in providing an improved cartridge for use in such systems.

The invention consists in the combinations and arrangements of parts hereinafter described and claimed.

20 The invention will be more readily understood by reference to the accompanying drawings forming a part of this specification, and in which,

Figure 1 is a partial vertical section of a 25 portion of a pneumatic tube system embodying my invention, Fig. 2, a bottom plan view of trigger mechanism employed in the construction, Fig. 3, a section taken on line $\alpha-\alpha$ of Fig. 2, Fig. 4, a side elevation, partially in section, of an improved cartridge 30 adapted to be employed in conjunction with the system, Fig. 5, a side elevation of the entry casing for a branch tube of the system, Fig. 6, a section taken on substantially line $35 y-y$ of Fig. 5, Fig. 7, an elevation at right angles to Fig. 5, Fig. 8, a section taken on substantially line $z-z$ of Fig. 7, and Fig. 9, a section corresponding with Fig. 6 but showing a modified form of construction.

40 The preferred form of construction as 35 illustrated in the drawings comprises a main tube 1 of a pneumatic tube system and a branch tube 2 leading thereto, said branch tube being designed to be located at a 45 station of the system. An entry casing 3 is secured about the lower end of branch tube 2 and a swinging closure 4 is secured to a shaft 5 mounted in casing 1. Closure 4 is provided with a leather packing plate 6 adapted to seat upon a valve seat 7 in casing 3 at the entry to tube 2, said closure being thus adapted to close the lower end of tube 2 to prevent entry of air thereto. At one end shaft 5 is extended beyond casing 3 55 and a cylindrical plate or collar 8 is secured

to said shaft. Plate 8 is provided with a notch 9 adapted to receive the end of a spring held catch or bolt 10, as indicated, said notch 9 being so positioned as to engage catch 10 when closure 4 is swung to open position, as indicated in dotted lines in Fig. 1. A coil spring 11 is secured to shaft 5 and arranged to hold closure 4 normally in closed position and to be wound up when said closure is swung to open position. A 60 wire 12 is connected with the end of catch 10 and extends upwardly through a guide tube 13 and is secured at its upper end to a trigger 14 pivotally mounted on tube 2 adjacent its juncture with main tube 1. A slot 65 15 is provided in the adjacent wall of tube 2 to permit trigger 14 to swing into and out of tube 2, as shown in Fig. 1. By this arrangement it will be observed that when closure 4 is open a cartridge may be inserted in the 70 lower end of tube 2 and the passage of said cartridge through tube 2 into tube 1 will operate trigger 14 to withdraw catch 10 and release closure 4 to permit closing of the 75 same under the influence of spring 11. 80

The lower end of casing 3 is provided with an inwardly swinging door 16 which is fixed to a shaft 17 mounted in casing 3. At one end shaft 17 is extended and carries a pinion 18 fixed thereto. Pinion 18 is connected by means of a chain of gears 19 with a similar pinion 20 secured to the corresponding end of shaft 5, the arrangement being such that when door 16 is swung inwardly and upwardly, closure 4 is swung 90 outwardly and downwardly to assume the relative positions indicated by dotted lines in Fig. 1. By this arrangement it will be observed that a cartridge may be readily inserted upwardly into casing 3 and that such 95 insertion will automatically open closure 4 to permit said cartridge to pass into the lower end of branch tube 2. A partial vacuum is always maintained in main tube 1 as is usual in such systems, so that when a cartridge is thus inserted in casing 3, it will be drawn by such vacuum upwardly through branch tube 2. When closure 4 is thus 100 swung to open position, catch 10 engages the notch 9 in plate 8 and locks said closure and door 16 in open position, thus permitting entry of air to the lower end of tube 2 and causing the cartridges to ascend in tube 2 under the influence of the vacuum in tube 1 as will be readily understood by those skilled 105 110

in the art. As the cartridge passes through tube 2 into the tube 1, trigger 14 is struck thereby and swung outwardly, thus drawing wire 12 upwardly and releasing catch 10 5 from notch 9, whereupon closure 4 and door 16 are closed automatically by spring 11, as will be readily understood, thus preventing entry of further air to main tube 1 and impairing the partial vacuum therein.

10 The cartridge employed in conjunction with the system above described, is illustrated in Fig. 4 and comprises a suitable metallic receptacle 21 having felt pads 22 arranged at each end and adapted to snugly 15 fit within tubes 1 and 2, so as to cause propulsion of said cartridge under the partial vacuum in the system, as will be readily understood. These pads are secured in position by means of guard plates 23 which are 20 made of slightly less area than said pads and are secured in position by means of screws 24 threaded in the ends of receptacle 21. By this arrangement it will be observed that pads 22 will constitute a good packing 25 for the cartridge in the tubes of the system and that trigger 14 will be struck by the edge of the forward guard plate 23 and be depressed thereby, thus preventing injury or material wear on the corresponding felt 30 packing 22.

In Fig. 9 I have illustrated a modified form of construction that can be used in conjunction with a system having cylindrical tubes, as distinguished from square tubes illustrated in the other views. Here 35 the casing 3' is made to fit the lower end of a cylindrical branch tube and closure 4' modified to correspond. Otherwise the construction and operation is identical with that before described.

40 While I have illustrated and described the preferred forms of construction for carrying my invention into effect, these are capable of variation and modification without departing from the spirit of the invention. I, therefore, do not wish to be limited to the 45 precise details of construction set forth, but desire to avail myself of such variations and modifications as come within the scope of the appended claims.

50 Having described my invention what I claim as new and desire to secure by Letters Patent is:

1. In a pneumatic tube system the combination of a main tube; a branch tube leading thereto; a closure for the end of said branch tube; and means located at the junction between said branch and main tubes and adapted to be operated automatically by a 55 cartridge passing through said branch tube and arranged to close said closure, substantially as described.

2. In a pneumatic tube system the combination of a main tube; a branch tube leading thereto; a spring held closure for the

end of said branch tube; means for locking said closure in open position; and trigger mechanism located at the junction between said branch and main tubes and adapted to be operated automatically by a cartridge 70 passing through said branch tube and arranged to release said closure, substantially as described.

3. In a pneumatic tube system the combination of a main tube; a branch tube leading thereto; a closure for the end of said branch tube; means located at the junction between said branch and main tubes and adapted to be operated automatically by a cartridge passing through said branch tube 75 and arranged to close said closure; a cartridge adapted to operate in said tubes; a pad at one end of said cartridge and fitting said tubes; and a guard plate covering said pad, substantially as described.

4. In a pneumatic tube system the combination of a main tube; a branch tube leading thereto; an outwardly opening spring held door normally closing the end of said branch tube; a catch arranged to hold said door in open position; trigger mechanism in said branch tube adapted to be operated by the passage of a cartridge therethrough and arranged to release said catch; an entry casing surrounding said closure; an inwardly swinging door giving access to said casing; and an operative connection between said door and said closure arranged to open said closure upon opening of said door, substantially as described.

5. In a pneumatic tube system the combination of a main tube; a branch tube leading thereto; an outwardly opening spring held door normally closing the end of said branch tube; a catch arranged to hold said door in open position; trigger mechanism in said branch tube adapted to be operated by the passage of a cartridge therethrough and arranged to release said catch; an entry casing surrounding said closure; an inwardly swinging door giving access to said casing; an operative connection between said door and said closure arranged to open said closure upon opening of said door; a cartridge adapted to operate in said tubes; 105 a pad on one end of said cartridge and fitting said tubes; and a guard plate covering said pad and adapted to contact with said trigger mechanism, substantially as described.

6. The combination with a branch tube for pneumatic systems, of a closure therefor; an entry casing surrounding said closure; a door for said casing; and an operative connection between said door and closure whereby opening of said door automatically opens said closure, substantially as described.

7. The combination with a branch tube for pneumatic systems, of an outwardly 130

opening closure therefor; an entry casing surrounding said closure; an inwardly opening door for said casing; and an operative connection between said door and closure whereby opening of said door automatically opens said closure, substantially as described.

In testimony whereof I have signed my name to this specification in the presence of two subscribing witnesses.

ALFRED HERZ.
